United States Patent Office.

WILLIAM HARTILL LAW, OF BIRMINGHAM, ENGLAND.

Letters Patent No. 103,059, dated May 17, 1870.

IMPROVEMENT IN STEAM-GENERATORS.

The Schedule referred to in these Letters Patent and making part of the same.

To all whom it may concern:

Be it known that I, WILLIAM HARTILL LAW, of Birmingham, in the county of Warwickshire, England, have invented a new and useful Improvement in Steam-Boilers; and I do hereby declare that the following is a full, clear, and exact description thereof, which will enable others skilled in the art to make and use the same, reference being had to the accompanying drawings forming part of this specification.

This invention relates to a novel method of constructing steam-boilers, whereby the steam-generating surface is greatly increased, a full and free circulation of water is secured, and the strength of the boiler increased.

The invention consists in securing, immediately above the fire-chamber, any suitable number of flat, radiating water-tubes, constructed and arranged as hereinafter more fully described.

In the accompanying plate of drawings—

Figure 1 represents a vertical central section of a steam boiler, constructed according to my invention.

Figure 2 is a horizontal section of fig. 1, through the line x x , showing the form and arrangement of the tubes.

Similar letters of reference indicate corresponding parts.

A is the outer shell of the boiler;

C represents an annular space around the inner shell D, which forms the water and steam-space of the boiler.

E represents the flat radiating water-tubes, which open into the annular space C, as seen in fig. 2.

These open flat tubes extend from the combustion-chamber F upward to about the water-line, when they slope back and conform in shape to the top of the inner shell D, as seen in the drawings.

G represents circulation-plates, or vertical partitions, in the tubes.

These plates extend upward from near the bottom ends of the tubes to the angle at h, near the water-line.

The whole exterior of the tube being fire-surface, the difference in temperature upon the inner and outer sides of the plates will cause a continual current through the inner space j, as indicated by the arrow.

K represents the steam-space of the boiler, and

L the door for the introduction of the fuel.

The smoke and products of combustion pass up into the central tube of chimney N, between the tubes E, which makes the entire outer surface of those tubes steam-generating surface.

The outer shell A is secured steam-tight around the flue N, as seen at o, while the base of that flue rests on the conical end of the inner shell D.

It will be seen that the conical portion of the inner shell, and also the flue, are contained in the steam-space K, so that the temperature of the steam is raised by its contact with those heated surfaces, and, consequently, dried or superheated before being used.

The circulation-plates may be permanently attached to the tubes E, or suspended therein.

In the former case they may be made to act as stays, and thus obviate the necessity of bolt-stays, as seen at p p, fig. 2. The tubes themselves act as stays to the interior shell D.

Having thus described my invention,

I claim as new and desire to secure by Letters Patent—

In combination with the steam-generator A, the flat, open water-tube E, constructed and arranged substantially as shown and described.

W. H. LAW.
